UNITED STATES PATENT OFFICE

ARTHUR V. STORM, OF MINNEAPOLIS, MINNESOTA

HOSPITAL TABLE

Application filed July 1, 1927. Serial No. 202,847.

My invention relates to adjustable tables and particularly to tables for use in hospitals and has for its object to provide a table which may be placed upon the bed of a patient, and while so supported, adjusted to accommodate the patient in all of his actions.

Another object of the invention resides in providing a table with end supports adapted to straddle the person of the patient and to rest directly upon the bed covers.

A still further object resides in forming the supports for said table with longitudinal runners adapted to slide along the bed covers to enable the patient to move the table without appreciable effort, said runners being arranged with upturned ends to facilitate the movement of the table upon the covers.

Another object of the invention resides in forming the table with separate end supports adapted to be adjustably secured to end members formed on said table, said supports being independently raisable to allow of regulating the height of the table and being independently tilttable to permit of adjusting the table to stand firmly upon the bed regardless of irregularities caused by the bed covers or the posture of the patient on the bed.

With the foregoing and other objects in view, which will appear in the following description, the invention resides in the novel combination and arrangement of parts and in the details of construction hereinafter described and claimed.

In the drawings:

Fig. 1 is a perspective view of a hospital bed illustrating the application of my invention thereto.

Fig. 2 is an end view of a table shown in Fig. 1 illustrating the top thereof at its maximum elevated position.

Fig. 3 is a front elevational view of the structure shown in Fig. 2.

Fig. 4 is an end view similar to Fig. 2 illustrating the table arranged as a reading table.

Fig. 5 is a view similar to Figs. 2 and 4 illustrating the table arranged as a book rack or easel.

In hospitals or sick rooms where patients are confined to their beds for any appreciable length of time, considerable difficulty and inconvenience is encountered in accommodating the patient in the performance of the various tasks of daily life. Heretofore, tables have been devised with the tops thereof adapted to overhang the bed proper, such tables being supported by a standard mounted upon the floor and such tables have been found inconvenient due to the fact that the patient is neither able to raise or lower the same or to adjust the angularity or position of the same relative to the bed, inasmuch as the fastening members for holding the parts in the desired locked positions are so situated as to be without the reach of the patient. In addition, the weight of the top on being adjusted in such types of tables require the operator to be in a standing posture beside the device, which is impossible where the patient is confined to his bed. My invention overcomes these difficulties by providing a simple and effective device whereby the patient may himself with practically no effort, adjust the table to meet with all of his requirements.

My improved hospital table which I have indicated in its entirety at A comprises a top 10 which is constructed with a ledge 11 extending along one of the edges of the same. This ledge extends upwardly above the surface of the top 10 and serves to retain articles placed thereon when the table is tilted, as will be presently described. The top 10 may be constructed of wood or any other suitable material, such as enameled metal, and the same is preferably constructed of a size somewhat shorter in length than the width of the bed so as to cause both of the supports therefor to rest inwardly from the edge of the bed proper as shown in Fig. 1. I have found that a very convenient size for use in conjunction with the ordinary hospital bed is approximately eighteen by thirty inches, though it can be readily comprehended that these dimensions may be varied to suit the requirements without departing from the spirit of the invention.

Across the underside of each of the ends

12 and 13 and top 10 are arranged two end members 14 and 15 which are rigidly attached to said top by means of screws or other fastening devices. These end members are constructed as best shown in Fig. 2 and consist of portions 16 and 17 extending completely across the top 10 and serving as cleats for stiffening and holding the top in proper position. Said end members are further constructed with depending arcuate portions 18 which are formed integral with the portions 16 and 17 and which extend considerably below the same. The arcuate portions 18 are formed with lateral slots 19 which commence at the centers of the said arcuate portions and extend outwardly toward the periphery of the same at right angles to the surface of the top 10.

In conjunction with the end members 14 and 15, I employ two supports 20 and 21 which co-operate with the end members 14 and 15 and are attached thereto, as will be presently described. These supports may be constructed of wood or metal, the same as the end members 14 and 15, and are arranged with arcuate portions 22 similar to the arcuate portions 18 of said end members except that the same extend in inverted relation thereto. The lower portions of the supports 20 and 21 are formed with runners 23 which have the extreme ends 24 and 25 turned upwardly as clearly shown in Fig. 2. The runners 23 and the arcuate portions 22 are formed integral, as disclosed, and have an appearance quite similar to that of the end members 14 and 15 except that the same are inverted. Commencing at the center of the arcuate portions 22 are arranged lateral slots 26 which extend outwardly toward the periphery of said arcuate portions and are at right angles to the lower edges 27 of said runners. The supports 20 and 21 are attached to the end members 14 and 15 by means of wing bolts 28 passing jointly through each of the pairs of slots 19 and 26 of the respective end members and supports, which bolts have screwed upon the ends of the same nuts 29 best shown in Fig. 3. Common bolts with wing nuts may be used for this purpose if desired or any other suitable form of fastening device.

By loosening the bolts 28, the end members 14 and 15 may be adjusted relative to the supports 20 and 21 so as to bring the top 10 of the table in any desired adjusted position. Upon tightening the said bolts the table becomes rigidly supported to the top thereof in the desired adjustment. Due to the arcuate formation of the portions 18 and 22 of end members 14 and 15 in the supports 20 and 21 considerable frictional contact may be had between the same, whereby the table may be rigidly supported without applying an excessive force in the tightening of the bolts 28. This is particularly advantageous for patients where the position of the patient is not par-

ticularly advantageous for manipulating the same and where the patient hasn't usually any too great strength to tightly turn the bolts. At the same time this permits of readily unloosening the bolts when it is desired to readjust the table.

In designing the end members 14 and 15 and the supports 20 and 21, as shown in the drawings, with the parts so proportioned as to give a maximum height of the top 10 as illustrated in Fig. 2 of approximately eighteen inches, and a minimum height of the top 10 as illustrated in dotted lines at 30 in Fig. 2 of approximately ten inches, I find that the table may be most advantageously utilized for hospital or sick room purposes so as to more conveniently accommodate the patient in all of his activities. It can readily be understood, however, that these dimensions are merely suggested and that the table may be constructed to be adjusted to any height desired.

For the purpose of illustrating the application of the invention, I have illustrated in Fig. 1 a bed B comprising a bedstead 31 having the usual mattress, bed clothing and a bed cover 32. In using the device the table A is positioned with the runners 23 of the supports 20 and 21 directly resting upon the bed cover 32 and straddling the person of the patient. When so disposed, the supports 20 and 21 rest with their edges 23 directly in contact with bed cover 32. It will be noted that the two supports 21 and 22 are independently adjustable relative to the end members 14 and 15 both as to height and tilt. This allows the table to be so adjusted as to cause the same to stand firmly upon the bed with the top in any desired position regardless of irregularities in the surface or slope of the bed caused by the bed clothes or by the posture of the patient. In such position the entire table A may be readily slid along said covers, the upturned ends 24 and 25 thereof facilitating such movement and preventing the runners 23 from catching in the cover 32. In adjusting the device, the patient can easily reach each of the bolts 28 and unloosen the same, after which the top may be adjusted to the required position and said bolts again tightened to hold the said top in fixed relation to the supports 20 and 21. When the table top 10 is lowered to its lowermost position as shown in dotted lines in Fig. 2, the arcuate portions 18 thereof also come in contact with the bed clothes. By making these portions arcuate the same permit of sliding the table along the bed without obstruction regardless of the tilt of top 10, said portion functioning in a manner similar to the upturned ends 24 and 25 of runners 20 and 21.

When it is desired to use the table for a dining table, the top 10 may be arranged in horizontal position as shown in Fig. 2, being disposed in any elevation within the limits illustrated in full and dotted lines in said

figure and depending upon the height of the patient and his posture in the bed. When it is desired to use the table for a writing table, the same may be tilted with the ledge 11 of top 10 downwardly toward the patient as shown in Fig. 1, which allows the patient to conveniently use the table for writing or similar purposes. If desired, the top 10 may be further tilted as illustrated in Fig. 4 to form a reading table in which position the book may be conveniently placed upon the top 10 with the lower portion thereof resting against the ledge 11. This carries the entire weight of the book, positioning the same at a convenient angle to be observed by the patient, and allowing the patient to fully relax. By swinging the top 10 to bring the bolts 28 at the upper ends of the slots 26 and the outer ends of the slots 19 as shown in Fig. 5, the table A may be arranged so as to form an easel or display rack for holding books or similar objects. When so arranged the table is disposed to the side of the patient or placed upon an adjoining table in the room where the articles held may be conveniently accessible. It will become evident that the table can be readily used for any of the ordinary requirements of a patient confined to bed such as making baskets, doing embroidery, or bead work, sewing, leather work, typewriting, or any of the other uses mentioned. The table forms a convenient support for a radio receiving device enabling the patient to have ready access to the tuning control so as to be able to operate the same without assistance.

The advantages of my invention are manifest. An extremely simple, strong and sturdy table is provided which can be quickly and effectively adjusted to meet all requirements. There are no parts to wear out or get out of order and requiring oil or other attention. There are no parts adapted to fall apart so as to inconvenience the user. The device is easily and quickly moved and adjusted and there is no possibility of injuring the patient or causing accidents to him while using the same. The table has an extremely low center of gravity and being supported at both ends is extremely rigid and stable. The device being entirely supported upon the bed does not offer obstructions to persons walking about the bed. Heavier articles such as typewriters and the like may be readily mounted upon the top of the table without danger of the same overturning. Whenever it is desired, the patient can push the table toward the foot of the bed where the same will be entirely out of the way allowing the patient to recline in the usual manner without interference.

Changes in the specific form of my invention, as herein disclosed, may be made within the scope of what is claimed without departing from the spirit of my invention.

Having described my invention, what I

claim as new and desire to protect by Letters Patent is:

1. A bed table comprising a top, a pair of end members secured to the top, each including a depending portion of arcuate formation, supports cooperating with said end members, each support being formed with a vertical slot therein, said arcuate portions of said end members being formed with radial-like slots, a fastening member joining each support with its respective end members and passing through the slot therein and the slot in the end member, the lower edges of said supports being upturned at both ends to form runners, said runners and arcuate portions of said end members permitting of the sliding of the table along the bed clothing without catching thereon, the fastening members and slots permitting of the individual adjustment of the supports angularly and also toward and from the top.

2. A bed table comprising a top, end members secured to the top, supports, one for each end member, means for attaching each support to its respective end member, whereby each support may be individually adjusted angularly and slidably relative to its respective end member, each support having an edge providing a runner, the same being upturned at each end thereof to cause the device to slide readily back and forth along the bed clothing.

In testimony whereof I have affixed my signature to this specification.
